Sam'l. D. Vose, of Albany, N.Y.
Letters Patent No. 575 - Dated June 28th 1853.
Ante-dated May 2nd 1853.

Ms. 575

The schedule referred to in these Letters Patent and making part of the same

To all whom it may concern:

Be it known that I, Sam'l. D. Vose, of the City & County of Albany and State of New York, have invented or produced a new design for a cooking stove (C) and I do hereby declare that the following is a full & exact description of the same, reference being had to the annexed drawings making part of this specification.

The invention not being easily described in words, reference to the drawings is made.

In the drawings, the letter T, refers to the top plate of the stove.

S	"	"	sides	"	"	"
E	"	"	front	"	"	"
H	"	"	hearth	"	"	"
D	"	"	doors	"	"	"
L	"	"	legs	"	"	"
OT	"	"	oven top plate	"	"	"
OF	"	"	oven front	"	"	"
OD	"	"	oven doors	"	"	"

My invention has no reference to any single moulding or ornament on said plates, but consists in the configuration & disposition of the ornaments in connection with the mouldings.

I claim no separate configuration or part.

What I claim as my invention & desire to secure by Letters Patent of the United States is the combination of Mouldings & ornaments as arranged in the cooking stove
(C) the whole forming an ornamental design.
